UNITED STATES PATENT OFFICE.

FRANK H. FAY, OF BROOKLYN, NEW YORK, ASSIGNOR TO AMERICAN TELEPHONE
AND TELEGRAPH COMPANY, A CORPORATION OF NEW YORK.

TELEGRAPH CIRCUITS.

Application filed October 8, 1923. Serial No. 667,377.

To all whom it may concern:

Be it known that I, FRANK H. FAY, residing at Brooklyn, in the county of Kings and State of New York, have invented certain Improvements in Telegraph Circuits, of which the following is a specification.

This invention relates to telegraph circuits and particularly to such circuits in which impulses of positive and negative polarity are employed for the transmission of signals.

It is one of the features of the invention to provide repeater sets for such circuits which will operate automatically and without "breaking" arrangements. The type of telegraph circuit for which the repeater set of this invention is adapted is one in which means are provided at the terminal stations whereby positive and negative signal impulses may be transmitted and whereby the line may be connected to ground through a polar receiving relay when the station is not sending. With such circuits the repeater set of this invention will give improved high speed automatic operation. Other features and details of the arrangements of the invention will appear more fully from the following detailed description thereof.

The invention may be more fully understood from the following detailed description, together with the accompanying drawing, in the figure of which is illustrated a circuit diagram of the invention.

In the drawing are shown two line sections L_1 and L_2 interconnected by the repeater set of this invention. It is understood that means are provided at the terminal stations with which these line sections are associated, whereby positive and negative signal impulses may be transmitted and whereby the line sections may be connected to ground through a polar receiving relay when the station is not sending. The repeater set comprises the polar relays 1, 2, 3 and 4. These polar relays have biasing windings b_1 , b_2 , b_3 and b_4 connected in a biasing circuit with battery 5. The relays also have actuating winding a_1 , a_2 , a_3 and a_4 which may be associated with the line sections. Relays 1 and 4 have the negative batteries 18 and 21, respectively, associated therewith, while relays 2 and 3 have the positive batteries 19 and 20, respectively, associated therewith. Pole-changing keys

K₁ and K₂ and a polarized sounder 22 are rewired through switches S₁, S₂ and S₃, respectively, for testing the repeater operation and for communicating purposes between the repeater station and the terminal stations.

The invention may be more fully understood from the following description of its operation. As has been pointed out heretofore, at each of the distant stations arrangements are provided for connecting and disconnecting the sending and receiving apparatus to and from the line thereat, so that with the circuit idle the line current will be zero. A slight biasing current is provided through one of the windings of each relay as follows: from ground and battery 5, winding b_4 , conductor 6, winding b_3 , conductor 7, winding b_1 , conductor 8, winding b_2 , conductor 9, to ground. In case there is no current through the actuating windings, as when the circuit is idle, this biasing current will hold the armatures of relays 1 and 4 against their left-hand contacts and the armatures of relays 2 and 3 against their right-hand contacts as shown in the drawing. If the station associated with line L_1 should now start to send, the impulses would be received at the repeater as follows: from line L_1 , left-hand contact of relay 1, conductor 10, right-hand contact of relay 2, conductor 11, winding a_2 of relay 3, conductor 12, winding a_4 of relay 4, conductor 13, to ground. A positive or spacing impulse from line L_1 will cause the armature of relay 3 to move over to its left-hand contact against the action of the biasing current. This received positive impulse will aid the biasing current through relay 4 to hold its armature against the left-hand contact. The operation of relay 3 will cause a positive or spacing impulse to be sent out over line L_2 as follows: from positive battery 20, left-hand contact of relay 3, conductor 14, left-hand contact of relay 4, and thence out over line L_2 . Similarly, a negative or marking impulse will aid the biasing current in relay 3 to hold its armature against its right-hand contact but will cause the armature of relay 4 to be moved over to its right-hand contact. This will cause a negative or marking impulse to be applied to the line L_2 from battery 21. In this manner the impulses received from line L_1 are repeated

over line L_2 . The impulses received at the repeater when the station associated with line L_2 is sending are repeated over line L_1 in a manner substantially the same as already described and no further description thereof will be given.

The pole-changing keys K_1 and K_2 and a polarized sounder 22 are wired through the switches S_1 , S_2 and S , respectively, for testing the repeater operation and for communicating purposes between the repeater station and the terminal stations. In order to test the operation of relays 1 and 2, or to send on line L_1 , the pole-changing key K_2 should be connected to the armature of relay 4 by the operation of the two point switch S_2 . The operation of key K_2 will now transmit impulses over the contacts of relays 4 and 3 and the windings of relays 1 and 2 to ground in the same manner as for the received impulses from line L_2 , operating relays 1 and 2 to repeat the signals to line L_1 . By throwing the switch S to its upper position the sounder 22 will be operated by the leak current from the outgoing signals over line L_1 . This will allow the operator to determine the condition of his relays and also to read the signals he may be transmitting. In testing the operation of the relays 3 and 4 or for sending out over line L_2 , the switch S_1 of the pole-changing key K_1 should be operated and the switch S of the polarized sounder 22 moved to its downward position.

While the arrangements of the invention have been disclosed as embodied in certain specific arrangements which are deemed desirable, it is understood that they are capable of embodiment in many and widely varied forms without departing from the

spirit of the invention as defined in the appended claims.

What is claimed is:

1. A telegraph repeater interconnecting two line sections, said repeater including two sets of polar relays having actuating windings and biasing windings, said biasing windings being so arranged that the actuating windings of one set of relays will be connected to one of the line sections over the contacts of all of the relays of the other set.

2. A telegraph repeater interconnecting two line sections, said repeater including two sets of polar relays having actuating windings and biasing windings, said windings being so poled and arranged that normally the actuating windings of one set of relays will be connected to one of the line sections over the contacts of all of the relays of the other set, and the actuating windings of said last mentioned set of relays will be connected to the other line section over the contacts of all of the relays of said first mentioned set.

3. A telegraph repeater interconnecting two line sections, said repeater including two sets of polar relays having actuating windings and biasing windings, said windings being so arranged and poled that normally the actuating windings of one set of relays will be connected to one of the line sections over the contacts of all of the relays of the other set, and means controlled by said actuating windings for applying to the line section sources of current of different potential.

In testimony whereof, I have signed my name to this specification this 3rd day of October, 1923.

FRANK H. FAY.
